UNITED STATES PATENT OFFICE.

CHARLES ADAMS, OF OLSTEIN, IOWA, ASSIGNOR OF ONE-HALF TO PETER J. A. SCHNOOR, OF HOLSTEIN, IOWA.

HEAD-LAMPS FOR VEHICLES.

1,134,090.

Specification of Letters Patent. Patented Apr. 6, 1915.

Application filed October 12, 1914. Serial No. 866,360.

To all whom it may concern:

Be it known that I, CHARLES ADAMS, a citizen of the United States, residing at Holstein, in the county of Ida and State of Iowa, have invented certain new and useful Improvements in Head-Lamps for Vehicles, of which the following is a specification, reference being had to the accompanying drawings.

This invention relates to certain improvements in head lamps for vehicles, and the object of the invention is to provide a novel and improved device of this general character whereby the lamps of the vehicle are caused to move in unison with and in the same general direction as the steering wheels of the vehicle whereby the rays of the lamps are disposed in the path of travel of the vehicle whether the same is proceeding in a straight line or rounding a curve.

The invention consists in the details of construction and in the combination and arrangement of the several parts of my improved head lamp for vehicles whereby certain important advantages are attained and the device is rendered simpler, less expensive and otherwise more convenient and advantageous for use, all as will be hereinafter more fully set forth.

The novel features of the invention will be carefully defined in the appended claims.

In order that my invention may be the better understood, I will now proceed to describe the same with reference to the accompanying drawings, wherein—

Figure 1 is a view in top plan of a motor vehicle, with an embodiment of my invention applied thereto; Fig. 2 is an enlarged detail view, partly in elevation and partly in section, of my invention as herein embodied; Fig. 3 is a fragmentary view in side elevation, on an enlarged scale, of the device as illustrated in Fig. 2; and Fig. 4 is an enlarged view in top plan of the operating arm herein embodied, with the coacting portion of the vehicle frame shown in fragment.

As disclosed in the accompanying drawings M denotes a motor vehicle of conventional construction having each of the forward projecting portions of the side beams 1 of the frame of channel formation, and to the lower flange whereof is secured through the medium of the spaced ears 2 the verti-

cally disposed sleeve 3 in which is rotatably supported a post 4 for supporting a lamp 5. It is to be observed that the lower extremity of each of the posts 4 is surrounded by an expansible member 10, herein shown as a conventional coil spring, interposed between the arm 6 and the lower end of the adjacent sleeve 3 in order to serve to absorb all shock imposed upon the post 4. The outer extremity of each of the arms 6 has pivotally engaged therewith a rod 7 which is in turn pivotally engaged with the bar 8 disposed transversely of the frame of the vehicle and supported for reciprocatory movement by the guide blocks 9 depending from the side beams 1. By this arrangement, it will be perceived that upon endwise movement of the rod or bar 8, the posts 4 will be caused to move in unison and in the same general direction together with the lamps 5 carried thereby.

Pivotaly engaged, as at 11, with the lower flange of one of the side beams 1 is the horizontally disposed arm 12 provided with the laterally and forwardly projecting extension 14 provided with an arcuate slot 15 adapted to accommodate a depending lug 16 carried by an extremity of the bar 8 whereby it will be perceived that upon rocking movement being imparted to the arm 12, the bar 8 will be moved endwise. Pivotaly engaged with the outer extremity of the arm 12 is a rod 17 having its opposite extremity operatively engaged with the rock arm 18 carried by the shaft 19, said shaft 19 being operatively engaged with the steering post 20 of conventional form. The rock arm 18 is also adapted to operate the steering mechanism (not shown) for the forward steering wheels S. I also find it in practice of advantage to have the extremities of the rods 7 angularly disposed as indicated at 21, and to have such angular portion positioned between the vertically spaced ears 22 carried by the bar 8 and through such ears 22 and the angular portion 21 is disposed a conventional pivot bolt 23.

From the foregoing description, it is thought to be obvious that a head lamp for vehicles constructed in accordance with my invention is of an extremely simple and comparatively inexpensive nature and is particularly well adapted for use by reason of the convenience and facility with which

it may be assembled, and it will also be obvious that my invention is susceptible of some change and modification without material departure from the principles and spirit thereof, and for this reason I do not wish to be understood as limiting myself to the precise arrangement and formation of the several parts herein shown in carrying out my invention in practice.

10. I claim:

1. In combination with a vehicle frame, of a lamp post rotatably supported by said frame, a bar movable transversely of the frame and capable of reciprocating movement, an operative connection between the post and the bar whereby reciprocating movement of the bar rotates the post, an arm pivotally connected with the frame and provided with a lateral extension having an arcuate slot, said bar being provided with a depending lug adapted to be accommodated within the slot, and means for imparting swinging movement to the arm.

2. In combination with a vehicle frame, a vertically disposed lamp post operatively supported by the frame, a reciprocating bar disposed transversely of the frame, a laterally directed arm carried by the lamp post, a rod in pivotal engagement with the bar and the arm of the post, an outwardly disposed arm pivotally engaged with the vehicle frame and disposed in substantially a horizontal plane and provided with a for-

wardly directed extension having an arcuate slot, said bar being provided with a depending lug adapted to be accommodated within the slot of the extension, and means for imparting swinging movement to the last named arm.

3. In combination with the frame of a vehicle, a vertically disposed sleeve operatively supported by the frame, a lamp post rotatably supported by the sleeve, an arm projecting laterally from the lower extremity of the post below the sleeve, an expandable member interposed between the arm and the adjacent extremity of the sleeve, a bar disposed transversely of the frame and mounted for reciprocating movement, a rod in pivotal engagement with the arm of the post and with the bar, an arm projecting outwardly and laterally from the vehicle frame and pivotally engaged therewith, said arm being provided with a forwardly directed extension provided with an arcuate slot, said bar being provided with a depending lug adapted to be accommodated within the slot of the extension, and means for imparting swinging movement to the last mentioned arm.

In testimony whereof I hereunto affix my signature in the presence of two witnesses.

CHARLES ADAMS.
